UNITED STATES PATENT OFFICE.

FRANK B. HENRY, OF PHILADELPHIA, PENNSYLVANIA.

BUILDING OR PAVING BLOCKS.

SPECIFICATION forming part of Letters Patent No. 752,070, dated February 16, 1904.

Application filed June 24, 1903. Serial No. 162,948. (No model.)

To all whom it may concern:

Be it known that I, FRANK B. HENRY, a citizen of the United States, residing at Philadelphia, in the county of Philadelphia and State 5 of Pennsylvania, have invented certain new and useful Improvements in Building or Paving Blocks, of which the following is a specification.

My invention relates to bricks or blocks for 10 building and paving purposes, and has for its object to provide blocks that will make a solid structure or formation.

My invention is especially useful in building masonry arches, columns, posts, incasing 15 wells, &c., as it dispenses with the necessity for frames in building the arches, while the well-casing is so formed and provided with projections that pierce the earth in the well-boring that it may be laid from the top down- 20 ward.

The advantages of my invention will fully appear hereinafter and by reference to the accompanying drawings, in which—

Figure 1 is an outside view of a segment of 25 well-casing involving my invention; Fig. 2, a horizontal sectional view; Fig. 3, a detail view of one of the binding and supporting blocks; Fig. 4, a detail view of one of the intermediate supporting-blocks, and Fig. 5 a 30 view showing my block adapted for use in flat structures or for paving-stones.

Referring to the drawings, in which similar reference characters indicate corresponding parts throughout the several views, A represents a binding and supporting block which is formed with a dovetail B on its lower edge and a correspondingly-shaped groove C on its upper edge, said dovetail and groove extending laterally of the wall. On one side edge of 40 the block is formed a dovetail D, while on the other side edge is formed a correspondingly-shaped groove E. The surface of the block on each side of dovetail D is formed with a channel F, having walls perpendicular to the 45 edge of the brick, while the surface of the block on each side of groove E is formed with a bead G, having perpendicular sides to fit snugly in channels F.

H represents a lateral spur or projection on

block A to fit into holes that may be dug in 50 the side of the well.

I represents other binding-blocks, that are formed exactly like blocks A except that no spur or projection H is provided on its outer 55 surface.

J represents the intermediate supporting-blocks, that have side dovetails K, correspondingly-shaped grooves L, channels M, and beads N corresponding in structure and arrangement with dovetails D, grooves E, channels F, and 60 beads G on binding-blocks A and I. Each block J is provided with an offset O, that extends downwardly below the bottom of said block J, and has a projection P that extends outwardly from the side of said offset and 65 when the blocks are properly placed, as shown in Fig. 1, rests on the top of spur or projection H.

Q represents other intermediate blocks, that are formed exactly like blocks J except that 70 they have not offsets O and projections P thereon.

It will be understood from this description that the casing of a well may be built downwardly by having every third vertical row of 75 blocks consist of binding-blocks with the binding and supporting blocks A arranged at suitable distances apart. The other two vertical rows of blocks consist of intermediate supporting-blocks J and intermediate blocks Q. It 80 will readily appear that the wall formed by my blocks will consist of tiers of blocks consisting of courses of binding-blocks and intermediate blocks abutting each side of the vertical row or superposed courses of binding-blocks 85 that are vertically adjustable independently of each other, so that the holes that may be made in the wall of the well to receive the projections H need not be in the same plane, as the different tiers will adjust themselves by gravity, though my invention will be more effective in operation if the bricks forming the courses of the various binding-blocks are on 90 the same plane, as the holes can then be dug on the same levels, or, if desired, staggered, 95 so as to divide the strain.

It will be understood that the inner side of each block is curved the arc of the circle it is

desired to make the casing of the well, while the outer sides of the blocks are curved or may be made flat, as desired.

I have described all the blocks that are used for a well-casing; but it will be readily understood that if an arch, column, post, &c., is desired the blocks A and J may be omitted and the structure built of blocks I and Q only. It will also be understood that if a double thickness of wall is desired another course of blocks I and Q may be used, having the arcs of the outside surface of the bricks used to fit the arc of the inside surface of the course just described. It will be understood, further, that the channels F and M and beads G and N will hold the block in place should by any chance the dovetails D or K become broken after installation.

In Fig. 5 is illustrated a set of blocks for use in flat walls and also adapted for use as paving-stones, the same reference characters referring to parts on these blocks that correspond to similar parts in the curved formation. As shown in said view, the spur or projection H extends beyond the sides of the block, while the offset O rests directly on said extended ends, thus dispensing with projection P.

Having thus described my invention, what I claim is—

- 30 1. In a binding-block, a dovetail on one end, a correspondingly-shaped groove on the other end, a dovetail on one side, and a correspondingly-shaped groove on the opposite side, substantially as shown and described.
- 35 2. In a building-block, a dovetail on one side, a correspondingly-shaped groove on the other side, the surface of the block abutting said dovetail channeled, and beads on said other side abutting said groove to fit into said channels, substantially as shown and described.
- 40 3. In a binding-block, a dovetail on one end, a correspondingly-shaped groove on the other end, a dovetail on one side, the surface of said side abutting said dovetail channeled, the walls of said channels being perpendicular to the surface of said side, a groove in the opposite side corresponding to the shape of said dovetail, and beads abutting said groove having perpendicular sides, substantially as shown and described.
- 45 4. In a building-block, a dovetail on one side, a correspondingly-shaped groove on the opposite side, the surface of the block abutting said dovetail channeled, the walls of said channels being perpendicular to the surface of said side, and beads on the opposite side of the block abutting said groove having perpendicular sides, substantially as shown and described.
- 50 5. In a binding-block, a dovetail on one end, a correspondingly-shaped groove on the other end, a dovetail on one side and channels in the surface of said side abutting said dovetail, a groove in the opposite side corresponding to the shape of said dovetail, and beads abutting

said groove to fit the channels aforesaid, substantially as shown and described.

6. A building-block for curved structures having curved sides, a dovetail on one edge, a correspondingly-shaped groove on the other edge, the surface of the block abutting said dovetail channeled, and beads on the grooved edge abutting said groove to fit said channels, substantially as shown and described.

7. A building-block for curved structures having curved sides, a dovetail on one edge, a correspondingly-shaped groove on the opposite edge, the surface of the block abutting said dovetail having channels therein with walls perpendicular to the surface of said edge, and beads on the opposite edge abutting said groove having perpendicular sides, substantially as shown and described.

8. A binding-block for curved structures having curved sides, a dovetail on one end, a correspondingly-shaped groove on the other end, a dovetail on one edge, and a correspondingly-shaped groove on the other, substantially as shown and described.

9. A binding-block for curved structures having curved sides, a dovetail on one end, a correspondingly-shaped groove on the other end, a dovetail on one edge and channels in the surface of said edge abutting said dovetail, a groove in the opposite edge corresponding to the shape of the dovetail on the other edge, and beads abutting said groove to fit the channels aforesaid, substantially as shown and described.

10. A binding-block for curved structures having curved sides, a dovetail on one end, a correspondingly-shaped groove on the other end, a dovetail on one edge and channels in the surface of said edge abutting said dovetail, said channels having walls perpendicular to the surface of said edge, a groove in the opposite edge corresponding to the shape of the dovetail on the other edge, and beads abutting said groove having perpendicular sides, substantially as shown and described.

11. In a building, series of blocks having a dovetail at one end, a correspondingly-shaped groove in the other end, a dovetail on one side, a correspondingly-shaped groove on the other, a spur or projection on individual blocks in said series, intermediate blocks between said series having a dovetail on one side, a correspondingly-shaped groove on the other, and offsets on individual intermediate blocks to rest on said spurs or projections, substantially as shown and described.

12. In a building, series of blocks having a dovetail at one end, a correspondingly-shaped groove in the other end, a dovetail on one side, the surface of said edge abutting said dovetail channeled, a groove in the opposite side corresponding to the shape of said dovetail, beads abutting said groove to fit the channels on the other side, a spur or projection on

individual blocks in said series, intermediate blocks between said series having a dovetail on one side and channels abutting said dovetail, a groove in the other side corresponding 5 in shape to the shape of the dovetail on the other side, beads abutting said groove corresponding to the shape of the channels aforesaid, and offsets on individual intermediate blocks to rest on said spurs or projections, 10 substantially as shown and described.

13. In a curved structure, blocks having their sides forming an arc of said structure, vertical series of said blocks having a dovetail at one end, a correspondingly-shaped 15 groove in the other end, a dovetail on one edge, a correspondingly-shaped groove on the other, and intermediate blocks between said series having a dovetail on one edge, and a correspondingly-shaped groove on the other, 20 substantially as shown and described.

14. In a well-casing, blocks having their sides forming an arc of a circle, vertical series of said blocks having a dovetail at one end, a correspondingly-shaped groove in the other end, a dovetail on one edge, a correspondingly-shaped groove in the other, and individual blocks in said series having a spur or projection on their outer sides, and intermediate blocks between said series having a dovetail on one edge, a correspondingly-shaped groove 25 in the other edge, and individual intermediate blocks having an offset thereon with projections to rest upon said spur or projection, substantially as shown and described.

In testimony whereof I hereto affix my signature in the presence of two witnesses.

FRANK B. HENRY.
